PORTRABLE FIREPLACE STOVE

Wendell H. Lovett, Bellevue, Wash., assignor of twenty-five per cent to Fred Bassetti, twenty-five per cent to John M. Morse, forty per cent to Wendell H. Lovett, and ten per cent to John R. Van Horne, all of King County, Wash.

Application April 19, 1954, Serial No. 30,076

Term of patent 14 years

(Cl. D81—7)

FIG. — |

FIG 4

FIG 3

FIG 2

To all whom it may concern:

Be it known that Wendell H. Lovett, a citizen of the United States, residing at Bellevue, Washington, has invented a new, original, and ornamental Design for a Portable Fireplace Stove, of which the following is a specification, reference being had to the accompanying drawing, forming a part thereof, in which:

Figure 1 is a perspective view of a portable fireplace stove showing my new design;

Figure 2 is a side elevation;

Figure 3 is a front elevation; and

Figure 4 is a top plan view of the same.

This application is a continuation-in-part of my application filed February 3, 1953, Serial Number D. 23,418, now abandoned.

I claim:

The ornamental design for a portable fireplace stove, as shown.
